UNITED STATES PATENT OFFICE.

PAUL YOHNS, OF NEW YORK, N. Y.

METHOD OF TRANSFERRING COLORS.

Application filed March 19, 1925. Serial No. 16,775.

To all whom it may concern:

Be it known that I, PAUL YOHNS, a citizen of Germany (having declared my intention of becoming a citizen of the United States), and a resident of the city of New York, borough of Manhattan, in the county and State of New York, have invented a new and Improved Method of Transferring Colors, of which the following is a full, clear, and ex-

10 act description.

This invention relates to the art of transferring colors from a pattern sheet onto a fabric such as linen, cotton, silk, woolen cloth, etc., and pertains more particularly to 15 those patterns sold in the stores to persons who wish to decorate their household linens, dresses, scarfs and other articles with flowers, ornaments and the like by means of an easily operated transfer pattern.

20 The invention has for its object the provision of a simple and convenient method of effecting the transfer, whereby the colors will be more efficiently incorporated into the fabric than hitherto has been possible.

25 It is my purpose to print or otherwise dispose on a pattern sheet a design in colors, using soluble dyes. In the operation of the pattern thus prepared, it is placed with the printed surface upward on a table or other 30 flat surface, and the sheet of material to which the design is to be transferred is placed thereover. A moist cloth is then disposed over the material to be printed and heat is preferably applied to the moist cloth, 35 this heat in most cases being very readily applied by running a hot iron over the top of the moist cloth. By reason of this simple operation, it is apparent that any ordinary housewife, after once reading the instructions, can readily make the proper transfers 40 without any difficulty.

In the drawings—

Figure 1 is a plan view of a sheet of paper or other thin material used as a pattern sheet; and

45 Figure 2 is a side elevation of the simple apparatus used to effect the transfer.

The form of the invention shown in the drawings is a preferred form, although it is understood that modifications in the construction and arrangement of the parts and in the character of the materials used may be adopted without departing from the spirit of the invention as set forth in the appended claims.

The purchaser of the pattern 1 places same

on a flat surface, printed side up; over this is laid the linen or other fabric 3 to be decorated right side down towards the pattern 1. Then a moist cloth 4 is laid over the 60 whole and a very hot pressing iron 5 is guided over this; the heat generates steam and this first chemically dissolves the printed stuff and then draws it up into the fibres of the fabric.

65 It is to be understood that the above arrangement may be reversed without departing from the principle of my invention, namely, the moist cloth 4 may be laid down first, the linen or other fabric 3 over this, 70 the pattern face down on the linen and then the hot iron guided over the back of the pattern; the heat of the iron, acting through all the layers, will, as before, generate steam in in the moist cloth 4 and this steam in the 75 same manner as before will be forced from the reverse side of the fabric 3 through the interstices and pores of its threads to act in the previously described way on all parts of the printed pattern simultaneously and at 80 right angles to the pattern surface. However, I prefer the first described arrangement, as it gives better results. Instead of a moist cloth, a sheet of blotting paper or any other material capable of holding moisture may be employed without departing from the spirit of my invention; the spirit of my invention residing in the method of generating steam or hot moisture at a place outside of but adjacent the back-surface of 85 the fabric to be decorated and then by means of pressure sending said steam or hot moisture at right angles all the way through the said fabric to its front surface and against the face of the pattern in contact therewith, 90 to act on the colors of the pattern first by dissolving them and then by drawing them 95 up into the fabric.

What I claim is:

1. A method of using a transfer pattern 100 having a design in soluble dyes disposed thereon, which comprises laying the pattern on a surface with the design upward, placing a fabric to which the design is to be transferred over said pattern, disposing a 105 moist piece of material over said fabric, and applying heat to the moist material.

2. A method of utilizing a transfer pattern having a design in soluble dyes disposed thereon, which comprises bringing the face 110 of the pattern into contact with the front side of the fabric to be decorated, then

bringing the reverse side of said fabric into contact with a piece of material which has previously been filled with moisture, and then applying heat to turn the moisture into steam.

3. A method of utilizing a transfer pattern having a design in soluble dyes disposed thereon, which comprises bringing the front side of the fabric to be decorated into contact with the face of the pattern, then bringing the reverse side of said fabric into contact with a piece of material which has previously been filled with moisture and then applying heat and pressure whereby the dyes are dissolved and drawn up into the fabric.
4. A method of using a transfer pattern having a design in soluble colors disposed thereon, which comprises bringing the back

side of the fabric to be decorated into contact with a piece of material which has previously been moistened, then bringing the face of the pattern into contact with the front side of said fabric, and then applying heat and pressure.

5. A method of transferring colors from a pattern onto a fabric, which comprises, by the application of heat, generating steam in a moist piece of material placed adjacent the back surface of the fabric to be ornamented, and then by pressure sending this steam through the said fabric to its front surface against which the face of the pattern is disposed whereby the colors are loosened from the transfer sheet and drawn up into the fibres of the fabric.

PAUL YOHNS.
